UNITED STATES PATENT OFFICE.

GEORGE F. ATWOOD, OF SWANTON, VERMONT.

SUSPENDER-LOOP.

SPECIFICATION forming part of Letters Patent No. 275,975, dated April 17, 1883.

Application filed January 24, 1883. (No model.)

To all whom it may concern:

Be it known that I, GEORGE F. ATWOOD, a citizen of the United States, residing at Swanton, in the county of Franklin and State of Vermont, have invented certain new and useful Improvements in Suspender-Loops; and I do declare the following to be a full, clear, and exact description of the invention, such as will enable other skilled in the art to which it applies to make and use the same, reference being had to the accompanying drawings, and to the letters and figures of reference marked thereon, which form a part of this specification.

This invention relates to certain improvements in suspender-loops; and it has for its objects to provide improved means for attaching the cord to the metallic portion of the device, as more fully hereinafter specified. These objects I attain by the means illustrated in the accompanying drawings, in which—

Figure 1 represents a view partly in section, showing my invention; Fig. 2, an elevation of the device; Fig. 3, a longitudinal sectional view thereof; Fig. 4, an elevation of a modification of my invention; Fig. 5, a detached view of a portion of said modification, and Fig. 6 a view of a metallic blank by means of which the cord is connected to the metallic portions of the device.

In the said drawings, the letter A indicates the cord, which is in the form of a loop, as usual, and B a metallic clamp by which the ends of the looped cord are held. The said clamp is constructed of a blank of sheet metal cut to the shape shown in Fig. 6, the side flaps, a, of which are bent over the ends of the cords, so as to bind the same in the clamp. The portion b is bent longitudinally around one side of the metallic wire loop C, and the prong d is bent down into the ends of the loop, so as to hold it securely in place.

As shown in Figs. 1, 2, and 3 of the draw-

ings, the ends of the metallic loop are provided with teeth or spurs, and are extended into the 45 clamping device, at each side of the ends of the cord-loop, and the extremities of said metallic loop are bent inward, so as to "bite" into the cord-loop and assist in holding the same. 50

As shown in Figs. 4 and 5, the metallic loop is replaced by a metallic frame, D, which is bent at c, so as to form a rearward projection, g, which is flattened and bent upward at its end. This extends into the clamping device, 55 and the upturned end serves, in conjunction with the other parts, to bind the ends of the looped cord in the clamping device. The ends of the said frame (indicated by the letter F) have secured to them the frame E of the buckle, 60 which is formed of stamped sheet metal and attached to the portions F of the wire frame, as indicated by Fig. 4 of the drawings.

Having thus fully described my invention, what I claim, and desire to secure by Letters 65 Patent, is—

1. In a suspender-loop, the combination, with the looped cord and wire loop, having toothed extremities which take into the cord, of the clamp provided with side and end flaps bent 70 over and partially around the cord and wire loop, whereby the parts are firmly secured together, substantially as described.

2. In a suspender-loop, the combination, with the looped cord and the wire having 75 pointed and bent extremities, the latter adapted to take into the cord, of the buckle-frame, and the clamp having side and end flaps adapted to be bent over and partially round the wire loop and cord, substantially as described. 80

In testimony whereof I affix my signature in presence of two witnesses.

GEORGE F. ATWOOD.

Witnesses:

BRYANT HALL,
HENRY A. BURT, Jr.
